UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

CORD-HANDLING MECHANISM FOR BUTTONHOLE-SEWING MACHINES.

Application filed January 23, 1926. Serial No. 83,210.

This invention relates to sewing machines of the buttonhole type adapted to sew a group of stitches and then come to rest. Machines of this type commonly embody 5 overseaming stitch-forming mechanism and a work-holder with means for relatively moving them to sew about a buttonhole. A cord-guide is customarily provided adjacent the sewing point to deliver a stay-cord or 10 gimp thread within the range of action of the stitch-forming mechanism so that such cord will be embraced within the overseam; the cord-guide being commonly formed as a small hole in the usual needle-throat member. Means are also commonly provided 15 for cutting the cord, as well as the sewing threads, after the sewing operation has been completed.

To avoid retrimming operations it is desirable, with machines of the class described, 20 that the cord and sewing threads be cut close to the last stitch in the work and a free end of cord is thus left protruding from the needle-throat member; the length 25 of this free end of cord being usually such that when the next sewing operation is started, such end projects objectionably from the beginning point of the overseam and requires to be retrimmed. This requirement 30 is troublesome and entails a wastage of cord. If the retrimming is done automatically, the accumulation of retrimmed cord ends tends to clog the stitch-forming mechanism and otherwise interfere with the proper operation 35 of the machine.

The present invention has for an object to avoid cord wastage and the difficulties incident to retrimming the cord. To this end means are provided for pulling the cord 40 back through the cord-guide so that the protruding end of the cord will be no longer than required to be safely bound by the initial stitches.

The cord pull-back mechanism may comprise a cord-engaging implement with means 45 for giving it a single to-and-fro movement at the proper time across the lead of the cord between the cord-guide and a suitable cord nipper; the latter device being actuated 50 to arrest the feed of the cord while the cord is engaged by the pull-back implement. After the pull-back implement has acted, the cord is left in a slack condition so that it

will run free of tension until the cord end is safely bound by the initial stitches. 55

In the accompanying drawings, Fig. 1 is a side elevation of a buttonhole sewing machine embodying the invention. Fig. 2 is a horizontal section through the bracket-arm standard showing the machine bed in plan. 60 Fig. 3 is a partial front end elevation of the machine. Figs. 4 and 5 are, respectively, plan and elevation views of the parts adjacent the sewing point at the end of the sewing period after the work has been 65 shifted to buttonhole cutting position. Figs. 6 and 7 are respectively plan and elevation views of the same parts at a slightly later stage when the turret carrying the lower 70 stitch-forming instrumentalities and cord-guiding means has been reversely rotated 180° to restore it to initial position; the cord-cutter being active at the close of this reverse rotation. Figs. 8 and 9 are respectively plan and elevation views of the same 75 parts at a still later stage when the stitched buttonhole is being acted upon by the buttonhole cutting mechanism. In Figs. 8 and 9 the cord pull-back and nipping elements are shown in operative engagement with the 80 cord.

For the purposes of the present disclosure the invention is described as embodied in an automatic eyelet-end buttonhole sewing machine, the frame of which comprises the hollow rectangular bed 1 from one end of which rises the standard 2 of the overhanging bracket-arm 3 terminating in the head 4.

The stitch-forming mechanism is constructed substantially in accordance with the 90 disclosure of the Allen et al. Patent No. 1,372,473, of March 22, 1921, and comprises the usual upper and under thread mechanisms. The upper thread mechanism comprises the reciprocating and laterally jogging needle 95 5 carried by the needle-bar 6 which is reciprocated by means of the link connection 7 with the crank 8 on the upper shaft 9. The shaft 9 is geared to the vertical shaft 10 which is driven by the lower main sewing 100 shaft 11. The under thread mechanism comprises the usual loop-taking devices 12 which, together with the usual needle-throat member 12a, are carried by the rotary turret 13. The loop-taking devices are actuated through 105 suitable connections with the shaft 11. The

turret 13 and needle-bar 6 are at times rotated in unison, as in sewing around the eyelet-end of a buttonhole, by means of the respective sector gears 14, 15, connected by links 16, 17, to cranks 18, 19, on the vertical shaft 20. The crank 18 Fig. 2 has a follower 21 entering the stitch-forming mechanism rotating groove 22 in the feed-wheel 23. During the sewing, the feed-wheel 23 is driven at a relatively slow speed, through suitable gear connections, not shown, by the sewing shaft 11. At other times the feed-wheel is driven at a higher speed by the rapid feed-shaft 24 which carries a gear 25 meshing with gear teeth on the feed-wheel and receives its motion through a clutch-connection, not shown, from the constantly rotating lower shaft 26. The period of action of the sewing shaft 11 is controlled by the usual stop-motion device 27 through which such shaft is connected to and disconnected from the constantly running belt-pulley 28.

The work-holder is constructed substantially in accordance with the disclosure of the Allen Patent No. 15,324, reissued April 4, 1922, and comprises the lower clamp-plates 29 and upper clamping feet 29' carried by the cross slide-plate 30 mounted in turn on the longitudinal slide-frame 31 adapted to slide in suitable ways in the machine bed. The cross slide-plate 30 and longitudinal slide-frame 31 are actuated by the usual connections with the feed-wheel as described in said reissued patent. When the machine is started the work-clamp occupies a position removed from sewing position. It is first shifted rapidly by the rapid feed-drive to sewing position, then is given a slower step-by-step motion as the sewing proceeds around the buttonhole and finally is given a rapid shift back to initial position, in which position the buttonhole and cord, as well as the under thread, are cut.

The buttonhole cutting mechanism is constructed substantially in accordance with the disclosure of said reissued patent and comprises the upper and under cutter-levers 32, 33, fulcrumed at 34 on the fulcrum-block 35, Fig. 2, to which travelling movements longitudinally of the bed 1 are given by means of the link-connections 36 from the cutter-advancing and -retracting cam 37 on the cutter-shaft 38. The cutter-levers are closed to cut the buttonhole by means of the cutter-closing cams 39, 40, on the cutter-shaft 38 which is actuated from the constantly running pulley 38' through the usual automatic one-revolution clutch-device 38'.

The under thread- and cord-cutter is constructed substantially in accordance with the disclosure of my Patent No. 1,579,200, dated Apr. 6, 1926. It comprises a scissors device including a blade 41 fixed to a carrier-lever 42 fulcrumed at 43 on the machine frame. A second blade 44 is fulcrumed at 45 on the

first mentioned blade 41 and has a tail-piece which carries a follower 46 entering a stationary cam-groove 47. When the lever 42 is swung about its pivot 43 the scissor-blades are projected in open relation transversely across the lead of the under thread and cord between the last stitch and the needle-throat member; the blade 41 grazing the under surface of the work and entering between such surface and the threads to be cut. During the final advancing movement of the scissors-device, the inclined end-portion 47a of the cam-groove 47 swings the blade 44 to cut the threads and cord close to the work, as shown in Figs. 6 and 7. In the particular machine illustrated the actuating mechanism for the scissors carrying lever 42 is constructed substantially in accordance with the disclosure of my copending application Serial No. 649,440, filed July 5, 1923, and comprises an actuating lever 48 fulcrumed at 49 on the frame-bracket 50 and connected at its front end by a link 51 to the scissors-carrying lever 42. The lever 48 has a follower 52 entering the cam-grooves 53 in the gear-member 25 on the rapid-feed shaft 24. The cam-groove 53 has an eccentric portion 53a which is timed to quickly advance and close the thread- and cord-cutting device after the work has been shifted from sewing to button-hole cutting position and before the button-hole cutting mechanism is tripped into action.

The cord *c* is led to the needle-throat member through a stationary cord-tube 54 mounted independently of the turret 13; thence across the under flat nipping face 55 and up through a guiding aperture 56 in a cord-nipper jaw member 57; thence to and through the usual cord delivery aperture in the needle-throat member 12a. A light tension spring 58 on the upper face of the jaw member 57 puts a light drag on the cord *c*. The nipper-jaw member 57 is mounted on the rotary turret 13 and at times is cooperatively related to the nipper-jaw member 59 fulcrumed at 60 on the machine frame. The nipper-jaw member 59 is formed as a lever having a tail piece 61 which is acted upon by a roll 62 carried by the cord pull-back bar 63 mounted on the travelling fulcrum block 35 which carries the buttonhole cutter-levers 32, 33. The tail-piece 61 of the cord-nipper lever 59 is formed with a cam 64 which is engaged by the roll 62 during the advance of the cutter-levers preparatory to the cutting of the buttonhole. Such engagement causes the nipper-jaw 59 to pinch the cord *c* against the under face of the jaw 57 and thus to arrest the feed of the cord. The cord pull-back 63 is formed at its forward end with a finger 65 and shoulder 66. During the advance of the buttonhole cutter-levers, the finger 65 passes under the cord between the cord-guide 56 and

the needle-throat member; the shoulder 66 engaging the cord and pulling a measured length of cord back through the cord delivery aperture in the needle-throat member.

- 5 The cycle of operations is as follows: After the sewing operation has been completed and the action of the rapid feed-shaft has carried the work from sewing to buttonhole cutting position, the parts are in 10 the position shown in Fig. 4; the nipper-jaw member 57 being spaced 180° from its companion jaw 59. The final movement of the rapid feed-shaft 24 acts through the cam-groove 22 in the feed-wheel to reverse- 15 ly turn the stitch-forming mechanism 180° as indicated by the arrow, Fig. 4, to restore it to starting position. As the turret 13 reaches initial position, carrying the nipper-jaw 57 directly over the jaw 59, the cam 20 portion 53^a in the gear 25 effects the quick advance and closure of the scissors 41, 44, Fig. 6, to cut the cord close to the end of the buttonhole. As soon as the cord is cut the buttonhole cutting mechanism is tripped 25 into action and, during the advance of the cutter fulcrum-block 35, the jaws 59, 57, are closed upon the cord and the shoulder 66 engages the cord, Figs. 8 and 9, and pulls back the cord end, leaving the cord slack between 30 the needle-throat member 12^a and the nipper-jaws 57, 59. When the buttonhole cutter-levers are retracted, the nipped-jaws 57, 59 are opened.

At the start of the next sewing operation 35 the initial stitches are formed so close to the beginning end of the cord that subsequent retrimming of such cord end is not required. The slackness in the cord between the spring 58 and the needle-throat member permits 40 the cord to run with the utmost freedom until the beginning cord end is safely bound by the initial stitches and all danger of such cord end slipping relative to such stitches is past.

45 Having thus set forth the nature of the invention, what I claim herein is:—

1. In a sewing machine of the buttonhole type, stitch-forming mechanism, a work-holder, means for relatively moving them 50 during the sewing, a cord-guide for delivering a cord within the range of action of the stitch-forming mechanism, means for relatively moving the stitch-forming mechanism and work-holder out of sewing relation 55 subsequent to the sewing operation, means for severing the cord, and positively actuated means out of strain-exerting engagement with the cord during the sewing for pulling back on the cord between sewing periods to shorten the severed cord end.

2. In a sewing machine of the buttonhole type, stitch-forming mechanism, a work-holder, means for relatively moving them 60 during the sewing, a needle-throat member, a cord-guide for delivering a cord within

the range of action of the stitch-forming mechanism, a cord-nipper open during the sewing, means for closing said nipper on the cord subsequent to sewing, and a cord pull-back device out of strain-exerting engagement with the cord during the sewing and acting on the cord between said nipper and said needle-throat member after the nipper has been closed.

3. In a sewing machine of the buttonhole type, stitch-forming mechanism, a work-holder, means for relatively moving them during the sewing, buttonhole cutting mechanism, a cord-guide for delivering a cord within the range of action of the stitch-forming mechanism, means for relatively moving the stitch-forming mechanism and work-holder out of sewing relation subsequent to the sewing operation, means for severing the cord, and means connected to 85 be operated by the buttonhole cutting mechanism for pulling back on the cord to shorten the severed cord end.

4. In a sewing machine of the buttonhole type, stitch-forming mechanism, a work-holder, means for relatively moving them during the sewing, a cord-guide for delivering a cord within the range of action of the stitch-forming mechanism, means for relatively shifting the stitch-forming mechanism and work-holder out of sewing relation, means for severing the cord between the cord-guide and the last stitch, a cord-nipping device ineffective during the sewing, a cord pull-back device, and means common 100 to said cord-nipping and pull-back devices for operating them at a predetermined time between sewing periods.

5. In a sewing machine of the buttonhole type, stitch-forming mechanism, a work-holder, a sewing shaft and connections for 105 relatively moving the stitch-forming mechanism and work-holder during the sewing, a cord-guide for delivering a cord within the range of action of the stitch-forming mechanism, a cord-cutter, a second shaft stationary during the sewing with means for driving it between sewing periods, and means mechanically connected to be driven by said second shaft for pulling back on the cord to shorten 110 the severed cord end.

6. In a sewing machine of the buttonhole type, stitch-forming mechanism, a work-holder, a sewing shaft and connections for 115 relatively moving the stitch-forming mechanism and work-holder during the sewing, a cord-guide for delivering a cord within the range of action of the stitch-forming mechanism, a cord-nipper, a cord-cutter, a second shaft stationary during the sewing with means for driving it between sewing periods, and means mechanically connected to be driven by said second shaft for actuating 120 said cord-nipper and for pulling back on the cord to shorten the severed cord end.

7. In a sewing machine of the buttonhole type, stitch-forming devices including upper thread mechanism, under thread mechanism, a rotary turret carrying the under thread mechanism, a cord-guide carried by said turret, a work-holder, means for relatively moving the stitch-forming mechanism and work-holder during the sewing, a cord-nipping device including coacting jaws one of which is carried by said turret and the other of which is mounted independently of said turret, said jaws being cooperatively related when the turret occupies a predetermined position, and a cord pull-back device adapted to act on the cord between said nipping device and said cord-guide.

8. In a sewing machine of the buttonhole type, stitch-forming mechanism, a work-holder, means for relatively moving them during the sewing, a cord-guide for delivering a cord within the range of action of the stitch-forming mechanism, a buttonhole cutter including a travelling fulcrum-block and cutter-levers fulcrumed on said block with means for advancing and retracting said block to carry the cutter-levers to and away from buttonhole cutting position, means for shifting the work-holder from sewing to buttonhole cutting position, a cord-cutter, and a cord pull-back device connected to be operated by the travelling movement of said buttonhole cutter fulcrum block.

9. The combination set forth in claim 8 with a cord-nipping device also connected to be operated by the travelling movement of said cutter-carrying fulcrum block.

10. In a buttonhole sewing machine, the combination with stitch-forming mecha-

nism, a work-holder, and means for relatively moving them to sew about a buttonhole, of a needle-throat member having a cord-guide, a cord-cutter operating at the close of a sewing operation, a cord-feed arresting device, and a cord pull-back device between the cord-feed arresting device and the needle-throat member, both of said devices being out of strain-exerting engagement with the cord during the sewing.

11. In a buttonhole sewing machine, the combination with stitch-forming mechanism, a work-holder, and means for relatively moving them to sew about a buttonhole, of a needle-throat member having a cord-guide, a cord-cutter operating at the close of a sewing operation, a cord pull-back element, and automatic means including a driving shaft mechanically connected to the cord pull-back element for moving the latter intermediate sewing periods.

12. In a machine of the buttonhole type, overseaming stitch-forming mechanism, a cord-guide for delivering a cord entirely within the overseam produced by said stitch-forming mechanism, a cord-cutter, and cord-engaging means having cord pull-back and slack-giving motions between sewing periods for pulling a measured length of cord back through the cord-guide and for producing slack in the cord before the start of the next sewing period to obviate the danger of slippage of the cord relative to the initial stitches.

In testimony whereof, I have signed my name to this specification.

EDWARD B. ALLEN.
